UNITED STATES PATENT OFFICE.

WILLARD F. DEATER, OF MEADVILLE, PENNSYLVANIA, ASSIGNOR TO McCROSKEY TOOL CORPORATION, OF MEADVILLE, PENNSYLVANIA, A CORPORATION OF PENNSYLVANIA.

CLAMPING DEVICE.

1,370,683.

Specification of Letters Patent.

Patented Mar. 8, 1921.

Application filed June 16, 1919. Serial No. 304,554.

To all whom it may concern:

Be it known that I, WILLARD F. DEATER, a citizen of the United States, residing at Meadville, in the county of Crawford and State of Pennsylvania, have invented new and useful Improvements in Clamping Devices, of which the following is a specification.

The clamp is particularly designed for use on the tables of milling machines, planers, shapers, etc. These tables are usually provided with slots through which T bolts may be passed. The clamp is designed to be secured by means of these bolts at any desired position on the table and to clamp the work both by side thrust against an abutment and at the same time to give to the work a downward thrust so as to assure its proper position on the table.

20 The invention is illustrated in the accompanying drawings as follows:—

Figure 1 shows an end elevation of a portion of a milling table with two clamps in place thereon.

25 Fig. 2 a side view of the clamp, partly in section to better show construction.

Fig. 3 an end view of the clamp, partly in section.

1 marks the table, 2 the milling tool and 3 a piece of work on the table.

The clamp has the base block 4. It is provided with a rib or tongue 5 which extends into the usual grooves arranged in the table. The base block is also provided with 35 the perforations 6 through which the usual bolts 6^a are passed for clamping the base block on the table.

The base block has an inclined front guiding face 7. This guiding face has a tongue 40 8 which extends from the bottom upwardly to about midway of the guiding face 7. A clamping block 9 has a guiding face corresponding in inclination to the face 7 and is 45 slidingly mounted on the base block in position to move on the guiding face 7. The clamping block has a groove 10 which has a sliding fit with the tongue 8 so as to assist in holding the block in alinement. The tongue 8 is provided with a screw socket 11, 50 the axis of which is in alinement with the guiding surface 7. A screw 12 operates in the socket 11 and has a shank 13 which extends through an opening 14 in the clamping block 9. The screw is provided with a

squared head 15 by means of which the 55 screw may be operated.

The portion of the clamping block having the opening 14 has a socket or opening 16 slightly larger than the perforation 14 and a spring 17 is arranged around the screw 60 and in this socket and rests against the end of the tongue 8. The socket is preferably of such depth as to receive the screw so that when the clamping block is at its lowermost position the shoulder 14^a of the clamping 65 block engages the end of the tongue before putting excessive pressure on the spring.

The clamping block has a clamping surface 9^a. It will be noted that the clamping block forms a wedge when in position on 70 the table against the work and this wedge may be made as powerful as it may be desired by varying the inclination of the surface 7. The downward movement of the block not only exerts a side thrust on the 75 work but also a downward thrust due to the downward movement of the clamping block. In Fig. 1 I have shown two of these clamping blocks one at each side of the work. In some instances, however, a mere abutment 80 may be used for one side of the work.

What I claim as new is:—

1. In a clamping device, the combination of a base block having a base surface and a guide surface inclined to the base surface, 85 said guide surface having a tongue thereon extending upwardly along the lower portion of said surface; a clamping block arranged on the guide surface and having a groove adapted to slidingly engage the tongue; a shoulder overlapping the tongue; and a screw extending through the shoulder and into the tongue.

2. In a clamping device, the combination of a base block having a base surface and a 95 guide surface inclined to the base surface, said guide surface having a tongue thereon extending upwardly along the lower portion of said surface; a clamping block arranged on the guide surface and having a groove 100 adapted to slidingly engage the tongue; a shoulder overlapping the tongue; a screw extending through the shoulder and into the tongue; and a spring arranged around the screw between the end of the tongue and the 105 shoulder.

3. In a clamping device, the combination of a base block having a base surface and a

guide surface inclined to the base surface, said guide surface having a tongue thereon extending upwardly along the lower portion of said surface; a clamping block arranged on the guide surface and having a groove adapted to slidably engage the tongue; a shoulder overlapping the tongue; a screw extending through the shoulder and into the tongue; a spring arranged around the screw between the end of the tongue and the shoulder; and devices for preventing an excessive pressure on the spring.

4. In a clamping device, the combination

of a base block having a base surface and a guide surface inclined to the base surface; a clamping block slidably mounted on the guide surface; a screw having engagement with the base block and clamping block and adapted to move when operated the clamping block on the guide surface whereby a side and downward thrust is exerted by the clamping block; and a spring adapted to retract the clamping block.

In testimony whereof I have hereunto set my hand.

WILLARD F. DEATER.
